UNITED STATES PATENT OFFICE.

ALFRED I. OSTRANDER, OF NEW YORK, N. Y.

ROTARY ENGINE.

SPECIFICATION forming part of Letters Patent No. 733,265, dated July 7, 1903.

Application filed November 28, 1902. Serial No. 133,001. (No model.)

To all whom it may concern:

Be it known that I, ALFRED I. OSTRANDER, a citizen of the United States, and a resident of the city of New York, (Williamsbridge,) 5 borough of the Bronx, in the county and State of New York, have invented a new and Improved Rotary Engine, of which the following is a full, clear, and exact description.

This invention relates to improvements in 10 rotary engines, the object being to provide an engine of this character of novel construction adapted to utilize all the energy of the steam, thus resulting in economy of the motive agent.

Other objects of the invention will appear 15 in the general description.

I will describe a rotary engine embodying my invention and then point out the novel features in the appended claims.

Figure 1 is a section on the line *v v* of Fig. 20 2 of the rotary engine embodying my invention. Fig. 2 is a section on the line *w w* of Fig. 1. Fig. 3 is a section on the line *x x* of Fig. 1. Fig. 4 is a section similar to Fig. 2, but showing the bearings in another position.

Fig. 5 is a section on the line *y y* of Fig. 1. Fig. 6 shows a valve-shifting cam employed. Fig. 7 is a section on the line *z z* of Fig. 1, and Fig. 8 is an end elevation of the engine.

Referring to the drawings, 1 designates a 30 fixed cylindrical casing in which a rotary driving-cylinder 2 is arranged. This driving-cylinder has a bearing at one end on a shaft 3, which is held stationary and passes through a steam-chest 4. The other end of the cylinder 2 is rigidly connected to a driving-shaft 5, having bearings in the end wall of the casing 1 and in a post 6. Between the said post and the casing a driving-wheel 7 is secured to said driving-shaft. Rigidly supported between the shafts 3 and 5 and eccentric thereto 40 is a shaft 8. This shaft 8 is secured at one end in a block 9, attached to the fixed shaft 3, and the other end of said shaft 8 is secured in a block 10, supported on the inner end of the shaft 5. Mounted to rotate on this fixed 45 shaft 8 is a cylindrical abutment 11. By thus mounting the abutment 11 its upper portion is at all times in engagement with the inner upper portion of the rotary cylinder 2. The abutment 11, however, rotates with said cylinder. Extended lengthwise through the cylinder 2 is a piston-plate 12. This plate is se-

cured at its ends to the heads of the cylinder and is in steam-tight connection with the cylinder for a greater portion of its length; but 55 in the other portion of its length is a rotary valve 13, which will be more fully described hereinafter. It will be noted that the shaft 8 has eccentric bearings, so that by turning it the bearing of the abutment 11 against the 60 cylinder may be adjusted.

The rotary abutment 11 has a longitudinal slot in which the piston-plate 12 moves, a suitable packing 14 being provided at the sides and carried by said abutment. The rotary valve 13 is cut out at its opposite sides to form ports, as indicated at 15 and 16, and it is arranged to rotate in a slot formed in the driving-cylinder 2, so as to permit of an exhaust to the outer side thereof, as will be 70 hereinafter described.

The ports 15 16 are designed for communication with a port 17, leading outward through the plate 12, and this port 17 communicates, through an opening in the head of the driving-cylinder 2, with a crescent-shaped chamber 18, which forms a port from which steam passes into the engine. The outer wall of this port 18 is eccentric to the axis of the driving-cylinder, the object being to regulate 80 the amount of steam admitted from a cut-off valve consisting of a disk 19, mounted to rotate on the fixed shaft 3 and having an opening 20 for receiving a chambered head 21, which has a movement relatively to the disk 85 19. Steam is admitted to the chamber of this head through perforations 22. This head 21 is mounted to rotate on an arm 23, connected to the disk 19, and formed on this head 21 is a gear 24, meshing with a gear 25, 90 rigidly attached to the shaft 3. Attached to the arm 23 is a gear 26, which surrounds the shaft 3 and meshes with a gear 27 on a shaft 28, which extends out through the outer wall of the steam-chest and has connected to its 95 outer end a pinion 29, which is engaged by a segment-rack 30 on a controlling-lever 31. This controlling-lever 31 is mounted to swing on an arm 32, and it is held in its adjusted position by means of a spring-pressed pawl 100 33, carried by the lever and engaging with an arc-rack 34 on the upper end of the arm 32.

I will now describe the means for shifting the valve 13 to cause the engine to rotate in

the desired direction. Surrounding the steam-chest within the casing 1 is a ring 35, which is designed to have a movement longitudinal of said steam-chest. In an annular channel 5 formed in the periphery of this ring 35 is a rotary ring 36, having an angular opening 37, which receives a spiral stem 38, extended from the end of the valve 13. From the ring 35 rods 39 extend outward through openings 10 in the outer wall of the steam-chest at the outer side of the chest and connect at their outer ends with crossed arms 40. From the hub of the arms 40 a finger 41 extends inward through an opening in a bracket 42, and 15 on the inner end of this finger is a roller 43, engaging in the channel of a cam 44. This cam has its shaft bearing in an arm 45, and on the shaft at the inner side of the cam is a pinion 46, meshing with the gear-wheel 29. The 20 channels in the cam-wheel are curved only for a short distance of their length, the greater length being straight around the wheel. It is obvious by this construction that when the lever 31 is turned in one direction the cam 25 will be operated to draw the rings 35 36 outward, consequently causing rotation of the valve 13 to admit steam to one side of the engine, and when the lever is moved in the opposite direction the rings will be moved inward to cause the reversing of said valve. 30 When the lever 31 is in an upright position, the roller 43 is midway of the curved portion of the cam and the valve 13 is in midway position, so that a very slight movement of the lever 31 serves to throw the roller in and out 35 of the straight portions of the cam and fixes the direction of rotation of the engine, and further movement of the lever to regulate the steam cut-off will have no further effect on 40 the valve 13. The ring 36 of course travels around the ring 35 with the driving-cylinder.

In operation steam passes into the steam-chest through an inlet 47. It then passes through said steam-chest and through the per- 45 forations 22 in the head 21 of the cut-off valve and then out through a port 48 in said head into the port 18 and thence into the cylinder. The steam passing through the port 16 will find an abutment at the junction or connec- 50 tion of the cylindrical abutment with the working cylinder, and the expansion against the piston-plate 12 will cause a rotary movement of the working cylinder, and during the movement the steam area between the two 55 parts 2 and 11 will be gradually increased about one-half a rotation and then will gradually diminish. The exhaust passes out through the port 15 and by impinging against baffle-plates 49 on the inner side of the cas- 60 sing 1 will react upon the outer surface of the cylinder 2 and materially aid in the operation. From this casing the exhaust passes out through a pipe 50.

The cut-off is regulated by the distance of 65 the port 48 from the shaft 3. It is obvious that as the port 48 approaches the shaft 3 it will pass over the port 18 in a longer arc, and

steam will be fed to the cylinder during the passage of the port 48 across the port 18. When the lever 31 is in vertical position, the 70 valve-head 21, with its outlet-port 48, is directly above and at its greatest distance from the shaft 3, the port 48 being on a straight line through the center of the shaft 3 and the center of the valve-head 21. The 75 port 48 is now entirely outside of the path of the port 18, and no steam will be admitted. When the lever is revolved to the position shown in Fig. 8, the rack 30 rotates the gear 29, and this gear by rotating the gear 27 80 causes a rotary movement of the plate or disk 19, carrying with it the valve-head 21, with its gear 24 meshed with the gear 25, fixed to the shaft 3. This causes the valve-head 21 to have a rolling motion and the port 85 48 to travel ahead of its former position on a straight line through the center of the shaft 3 and valve-head 21 and also to approach the shaft 3 and will now be in the position shown in Fig. 3.

When the engine is at rest on a dead-center, as shown in Figs. 2 and 3, the continued movement of the lever 31 in the direction indicated in Fig. 8 will cause the port 48 to follow the edge of the crescent-shaped 95 port 18 until it occupies a position between the horns of the crescent-shaped port where the lever 31 is at the end of the arc. In reversing, the port 48 travels around the other horn of the crescent to this same position between the horns. Now it is evident that as the crescent-shaped port 18 revolves about the shaft 3 as a center the port 48 will pass over the crescent-shaped port 18 and admit steam through an arc whose length varies 105 with the various positions that the port 48 may take, from zero when the port 48 is at the top of the crescent-shaped port 18 to a practically full revolution when the port 48 is at the lower position, between the horns of 110 the crescent-shaped port 18.

From the above it is apparent that no steam will be admitted to the cylinder by the movement of the lever 31 in either direction when the piston-plate 12 is in the point of tangency 115 of the abutment 11, as shown in Fig. 2, but that a small movement of the cylinder in the proper direction will bring the port 48 over the port 18, and steam will be admitted to cause rotation of the cylinder. In other 120 words, the steam is always cut off during the passage of the piston-plate 12 through the point of tangency of the cylinder and the abutment. When the engine comes to rest in any other position but that shown in Fig. 125 2—as, for instance, the position shown in Fig. 4—the movement of the lever 31 sets the valve 13 in the proper direction, and the port 48 will come over the crescent-shaped port 18 at some point in its travel, admitting steam to 130 the cylinder.

When it is essential to absolutely avoid a dead-center, two engines may be put on the same driving-shaft, with piston-plates dis-

posed at one hundred and eighty degrees with each other.

Having thus described my invention, I claim as new and desire to secure by Letters Patent—

1. A rotary engine, comprising a fixed casting, a cylinder mounted to rotate in the casting, a cylindrical abutment arranged eccentrically in the cylinder, a piston-plate connected to the cylinder and movable into and out of an opening in the cylindrical abutment, and a controlling-valve carried by said piston-plate, substantially as specified.

2. A rotary engine, comprising a fixed casting, a working cylinder mounted to rotate therein, a cylindrical abutment eccentrically arranged in said cylinder and having a longitudinal slot or opening, an abutment-plate secured in the cylinder and movable into and out of said slot or opening, a valve for controlling the inlet of steam to the interior of the cylinder and controlling the exhaust therefrom, and means for shifting said valve, substantially as specified.

3. A rotary engine, comprising a fixed casting, a working cylinder mounted to rotate therein, a cylindrical abutment eccentrically mounted in the cylinder, the said abutment having a longitudinal slot, a piston-plate attached to the interior of the cylinder and adapted to pass into and out of said slot, the said plate being provided with an inlet-port, a rotary valve for controlling said port, and means for controlling the admission of steam to said port, substantially as specified.

4. A rotary engine, comprising a fixed casting, a working cylinder mounted to rotate therein and having a port through one of its heads and a port or opening in its periphery, a piston-plate extended lengthwise in the cylinder and secured thereto, a rotary valve having ports at its opposite sides the said valve being arranged in line with said plate, said plate having a port for connecting the ports of the rotary valve with a port through the head of the cylinder, means for regulating the admission of steam into said cylinder, a fixed shaft within the cylinder and eccentric thereto, and a rotary abutment mounted on said fixed shaft, and having an opening to receive the piston-plate, substantially as specified.

5. A rotary engine, comprising a fixed casting, baffle-plates on the inside of said casting, a cylinder mounted to rotate in the casing, a cylindrical abutment arranged eccentrically in the cylinder so as to engage at all times with the cylinder, said cylindrical abutment having a longitudinal opening or slot, a piston-plate secured in the cylinder and movable in said opening or slot, the said plate having a port and the said cylinder having a port in one of its heads for communicating with the port in the plate, and also having a port in its periphery, and a rotary valve for controlling the entrance of steam to the cylinder and also controlling the exhaust from

the cylinder whereby said exhaust may operate against the said baffle-plates, substantially as specified.

70

6. A rotary engine, comprising a fixed casting, a cylinder mounted to rotate therein, and having a port in its head, the said port comprising a crescent or curved depression or port in the outer surface of the head, a cylindrical abutment eccentrically mounted in the cylinder having a longitudinal opening or slot, a piston-plate secured in the cylinder and movable in said opening or slot, the said plate having a port for communicating with a port through the head of the cylinder, a valve for controlling the inlet of steam to the cylinder from said port in the plate, a disk mounted for rotary movement on a fixed shaft, the said plate or disk having a port to communicate more or less with said crescent-shaped depression, and means for causing a rotary movement of said disk, substantially as specified.

7. A rotary engine, comprising a fixed casting, a cylinder mounted to rotate in said casting, a cylindrical abutment eccentrically mounted to rotate in said cylinder, the said abutment having a longitudinal opening, a piston-plate secured within the cylinder and movable in said opening, the said plate having a port communicating with a port in the head of the cylinder, a rotary valve for controlling the inlet of steam to the cylinder through said port in the plate, the said port in the head of the cylinder comprising a crescent-shaped depression in the outer face of the head, a disk mounted to rotate on a fixed shaft and having a port to communicate more or less with said crescent-shaped depression, a chambered head carried with said disk and having a port for communication with a port of the disk, the said chamber also having an inlet for receiving steam from the steam-chest, means for causing a rotary movement of the disk, and means for causing a swinging or rotary movement of the said head, substantially as specified.

8. A rotary engine, comprising a fixed casting, a cylinder mounted to rotate in the casting, a steam-chest at one end of the casing, a cylindrical abutment mounted eccentrically in the cylinder and having a longitudinal opening at one side, a piston-plate secured in the cylinder movable in said opening, the said piston-plate having an inlet-port, a rotary valve for controlling said port, a spirally-disposed stem for said valve, a ring movable lengthwise of the steam-chest and having an angular opening to receive said stem, and means for moving the ring on the steam-chest, substantially as specified.

9. A rotary engine, comprising a casing, a cylinder mounted to rotate in the casing, a cylindrical abutment eccentrically mounted in the cylinder and having an inlet-port for steam, a rotary valve for controlling said port, a spiral stem from said valve, a steam-chest at one end of the casing, a channeled

115

120

125

130

- ring movable lengthwise of said steam-chest, a ring arranged in the channel of the first-named ring, and having an opening to receive the valve-stem, rods extended outward 5 from the channeled ring, arms connecting said rods, a cam, a connection between said cam and the arms, and means for imparting a rotary motion to the cam, substantially as specified.
10. A rotary engine, comprising a casing, a cylinder mounted to rotate in the casing and having a port in one of its heads and a port at one side, a cylindrical abutment eccentrically mounted in the cylinder and having 15 a longitudinal slot in its periphery, a piston-plate secured in the cylinder and movable in said slot, the said plate having a port providing communication between the two ports of the cylinder, a rotary valve for controlling 20 said port, a spiral stem extended from the valve, a steam-chest at one end of the casing, a ring mounted to move on said steam-chest

and an opening to receive said stem, a fixed shaft on which one end of the cylinder has a bearing, a disk mounted to rotate on said 25 fixed shaft at the outer side of the cylinder, said disk being provided with a port for communicating with a port through the head of the cylinder, a controlling-lever, gear connections between said controlling-lever and 30 said disk, a chambered head mounted for rotary motion relatively to said disk, the said chambered head having inlet and outlet ports, a gear on said head, and a gear fixed to the shaft and engaging with the gear on the head, 35 substantially as specified.

In testimony whereof I have signed my name to this specification in the presence of two subscribing witnesses.

ALFRED I. OSTRANDER.
